UNITED STATES PATENT OFFICE

PAUL D. PRENTISS, OF WHITE PLAINS, NEW YORK, ASSIGNOR TO JOHNSON & JOHNSON, OF NEW BRUNSWICK, NEW JERSEY, A CORPORATION OF NEW JERSEY

HANDRACK FOR ADHESIVE TAPE

Application filed May 28, 1930. Serial No. 456,663.

This invention relates to devices or holders for adhesive tape and the like and was devised with the object of simplifying the handling of the tape and the application thereof in service.

The nature of the invention consists in the provision of a simple and inexpensive handrake embodying a handle co-extensive with a spindle constructed to receive a facto-
10 ry loaded core of adhesive tape and having guards at each end whereof one is removable to permit the application of the tape, the guards being of polygonal form so that the rack will not have a tendency to roll or
15 creep.

The preferred embodiment is illustrated in the accompanying drawings forming a part hereof, wherein

Figure 1 is a view partly in elevation and
20 partly in longitudinal section of the improved handrake and tape assembly.

Fig. 2 is a side elevational view of the removable guard and

Fig. 3 is an end view thereof.

The improved handrake embodies a tubular shank or spindle 5 equipped at one end with a handle 6 and with a fixed guard 7, and at the other end with a removable guard 8. The latter may be secured relatively to the shank or spindle in any suitable way, but under the preferred practice, guard 8 is formed or provided with a tubular extension 9 adapted to telescope the end of the spindle and to have pin and slot connection therewith as indicated at 10. In order to prevent creeping or rolling of the handrake when not in use, the edges of the guards are of polygonal conformation as at 11. The tubular shank or spindle 5 is intended to receive a roll of adhesive tape 12 having a core 13 adapted to fit the spindle with more or less friction as may be desired. When the roll is exhausted, it may be replaced by a fresh roll by simply removing the detachable guard, applying a new roll and then securing the guard to place.

Having described the invention, what is claimed, is:

A completely portable rack for handling
50 adhesive tape in roll form, comprising a tubu-

lar shank provided near one end with a fixed guard the transverse extent of which exceeds the diameter of the adhesive roll with which the rack is to cooperate, said shank being extended beyond the guard in the form of a handle, a complemental guard having a tubular extension for fitting snugly within the tubular shank to arrange such complemental guard substantially in contact with the free end of the shank, and cooperative means carried by the shank and tubular extension to removably secure the complemental guard in place.

In testimony whereof I affix my signature.
